(57) **CLAIM**

We claim the ornamental design for a waste receptacle cinch, as shown and described.

DESCRIPTION

FIG. 1 is a perspective view of a waste receptacle cinch showing our new design;

FIG. 2 is an enlarged perspective view thereof;

FIG. 3 is a front view thereof;

FIG. 4 is a rear view thereof;

FIG. 5 is a bottom view thereof;

FIG. 6 is a top view thereof;

FIG. 7 is a side view thereof;

FIG. 8 is the other side view thereof;

FIG. 9 is another perspective view of the waste receptacle cinch showing our new design;

FIG. 10 is an enlarged perspective view thereof;

FIG. 11 is a front view thereof;

FIG. 12 is a rear view thereof;

FIG. 13 is a bottom view thereof;

FIG. 14 is a top view thereof;

FIG. 15 is a side view thereof; and,

FIG. 16 is the other side view thereof.

The broken lines in the figures are for the purpose of illustrating environment and form no part of the claimed design. The dash-dot broken lines in the figures define the bounds of the claimed design and form no part thereof.

1 Claim, 16 Drawing Sheets
